UNITED STATES PATENT OFFICE

1,992,624

ELECTRIC IRON AND STAND

Rudolph Kovac, Chicago, Ill., assignor to American Automatic Devices Co., Chicago, Ill., a corporation of Illinois

Application September 5, 1933, Serial No. 688,095

8 Claims. (Cl. 219—25)

My invention relates to electric irons and stands and has for its object the provision of a new and improved form and arrangement of parts by which an electric current may be fed to the iron by a cord attached directly to the iron or alternatively by a cord attached to the stand upon which the iron rests from time to time in the course of ironing operations. It is one of the objects of my invention to provide improved current feeding means on the iron comprising two sets of contact members projecting outwardly from the iron in different directions, one set in substantially vertical position for engagement with the plug of the cord when the cord is attached directly to the iron and the other set in approximately horizontal position for engagement with the contact members of the stand when the cord is attached thereto rather than to the iron. It is one of the objects of my invention to provide an improved arrangement of shielding means adapted in one position to shield both of said sets of contact members by cooperation with the plug of the cord when attached directly to the iron and adapted in another position to shield both of said sets of contact members by cooperation with the current feeding means on the stand when the iron is being used with the cord attached to the stand.

It is another object of my invention to improve devices of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing,—

Fig. 1 is a side view of my improved iron and stand with the cord attached to the stand for heating the iron;

Fig. 2 is a view similar to Fig. 1, but partly broken away, and showing the iron in a slightly different position on the stand so as to prevent delivery of electric current to the iron;

Fig. 3 is a view similar to Fig. 2, but showing the cord attached directly to the iron rather than to the stand;

Fig. 4 is a view of the rear end portion of the iron as seen from one side, with certain of the parts broken away; and

Fig. 5 is a cross sectional view taken at line 5—5 of Fig. 4 upon a slightly enlarged scale.

Referring now to the several figures of the drawing, in which corresponding parts are indicated by the same reference characters, 10 indi-

cates the body of a stand supported at its rear end by short legs 11 and at its front end by one or more longer legs 12 so as to stand normally in slightly inclined position. At the rear end of the stand, a bracket 13 projects upwardly carrying at its upper end current feeding means 14 comprising upper and lower insulation members 15 and 16 respectively held in position upon the bracket by means of a bolt 17 (see Fig. 3) and supporting in position two contact members 18 provided at their rear end portions with contact pins 19 which project beyond the insulation members 15 and 16,—only one of said contact members 18 being shown in the drawing. In the arrangement shown a shield device 20 in the form of a flattened sleeve is secured in position about the contact pins 19, being held in position by means of a plate 21 formed therewith and extending between the bracket 13 and the insulation member 16. The arrangement is such that a standard plug 22 of a cord 23 is adapted to fit upon the contact pins 19 for feeding electric current thereto, as is shown in Figs. 1 and 2. The contact members 18 are preferably of the type illustrated in the copending application of Narodick, Serial No. 554,745, such contact members forming in and of themselves no part of my invention.

In Figs. 1, 2 and 3, I have shown an electric iron 24 of any approved type in position upon the stand 10 in a variety of different relations thereto. Such iron 24 is provided with a handle 25 of wood or other suitable material supported in position between the upper ends of the arms 26 of a yoke secured in position upon the iron by means of bolts 26a. In the arrangement shown the rearmost arm 26 is provided with a housing member 27 upon its rear face, such housing in the arrangement shown being formed of sheet metal comprising a front wall portion 28 and side wall portions 29 and 30 formed integrally with the front wall portion 28. In the arrangement shown the housing is secured in position by means of bolts 31 having screw threaded relation to the arm 26. The arrangement is such that the housing is effectively closed at its front face and at both side faces.

As is clearly shown in Figs. 4 and 5 the iron 24 is provided at its rear end portion between the side walls 29 and 30 of the housing with contact pins 32 and 33 which are of standard size and relationship for receiving thereon the plug 22 of the cord 23 which has been already referred to as having effective engagement with the pins 19. The pins 32 and 33 are mounted in substantially

vertical position on the iron so as normally to support the cord 23 well above the base of the iron when the plug is positioned upon such pins 32 and 33 as illustrated in Fig. 3.

5 In the arrangement shown in Fig. 4, the pins 32 and 33 extend upwardly through an insulation member 34 of wood or other suitable material which extends upwardly through an opening in the wall of the housing comprising the body of the iron, as is usual in such constructions. Nuts 35 and 36 upon said pins serve to clamp auxiliary contact pins 37 and 38 in position upon the pins 32 and 33 respectively, such contact pins 37 and 38 being arranged in substantially horizontal 15 position at right angles to the position of the pins 32 and 33 so as to extend rearwardly in substantially parallel relation to the side walls 29 and 30 of the housing 27.

For completing the enclosure about the contact pins carried by the iron to the extent necessary for effective results in my improved arrangement, I have provided a hood member 39 which is pivotally mounted upon the housing 27 by means of rivets 40 as hereinafter described. Such hood 39 comprises side wall portions 41 and 42 each in the form of a sector, such side wall portions being connected at their outer ends by a curved wall portion 43, as is best shown in Fig. 4, the rivets 40 having engagement with the side walls 29 and 30 of the housing and the side walls 41 and 42 of the hood. The pivotal connection by means of the rivets 40 is such that the hood 39 is adapted to stand normally in any adjusted position with respect to the housing, so as to close the housing at its upper end as shown in Fig. 1 or to close the housing at the rear as shown in Fig. 2, the hood being held yieldingly in adjusted position by friction.

In the normal use of the iron 24, it is placed in position upon the stand 10 with the plug 22 of the cord mounted upon the contact pins 19 in the position as shown in Fig. 1. The arrangement is such that when the iron 24 is in position upon the stand, with the hood 39 in its uppermost position as shown in said Fig. 1, the contact pins 37 and 38 stand in effective engagement with the contact members 18 of the current feeding means 14. In the arrangement as shown in Fig. 1, current is being fed to the heating element of the iron at all times when the iron is in position on the stand. When and if for any reason it may be desirable to place the iron upon the stand without any additional current being fed to the heating element, this can be effected conveniently by first moving the hood 39 to its lowermost position so as to hold the iron in slightly advanced position upon the stand and to prevent engagement of the contact pins 39 with the contact members 18,—as is illustrated in Fig. 2 of the drawing. If at any time it is desirable that current be fed to the heating element at all times during the ironing operation, the hood 39 would then be moved to its lowermost position as shown in Fig. 3 so as to permit the plug 22 to be inserted upon the contact pins 32 and 33 of the iron in lieu of being mounted upon the pins 19 of the stand.

From the above description, it will be seen that by the use of my improved arrangement the contact pins 32 and 33 and the horizontal contact pins 37 and 38 are at all times effectively shielded during the feeding of current thereto. With the parts in the relation as shown in Fig. 1, the hood 39 prevents access to the contact pins of the iron from above, while the insulation members 15 and

16 prevent access to such pins during the time when the iron is in position as shown in Fig. 1, and there is, therefore, no likelihood of a person being shocked or having the fingers burnt by coming into contact with the pins 32 and 33 or the pins 37 and 38. When the hood 39 is in its lowered position as shown in Fig. 3, the housing parts, by cooperation with the plug 22, effectively shield the contact pins at all times when current is being delivered through the cord and plug, 10 and shocks and burns to the operator by the fingers coming into contact with either set of pins is also prevented.

By my arrangement I have provided a very convenient and effective arrangement which can 15 be provided readily and cheaply and which is effective for any one of the three uses normally contemplated as above described.

While I prefer to employ the form of device as shown in my drawing and as above described, it 20 is to be understood that my invention is not limited thereto except so far as the claims may be so limited by the prior art, it being understood that changes might well be made in the form and arrangement of the parts without departing from 25 my invention.

I claim:—

1. In an arrangement of the type described, the combination of an electric iron having at its heel portion two sets of contact members one 30 set projecting outwardly in a substantially vertical direction and the other set projecting outwardly in a substantially horizontal direction, and shielding means on said iron substantially opposite the outer ends of the contact members of one set and movable to alternative positions substantially opposite the outer ends of the contact members of the other set.

2. In an arrangement of the type described, the combination of an electric iron having at 40 its heel portion two sets of contact members one set accessible from one direction and the other set accessible from a substantially different direction, and a hood movably mounted on said iron adapted in one position to prevent access to one set of contact members from one direction and adapted in an alternative position to prevent access to the other set of contact members from another direction.

3. In an arrangement of the type described, 50 the combination of an electric iron having contact means thereon at its rear end portion and capable of contacting current supply means extending either from the rear or from above, and shielding means movably mounted on said iron adapted in one position to shield said contact means from the rear and adapted in an alternative position to shield said contact means from above.

4. In an arrangement of the type described, 60 the combination of an electric iron having contact means thereon at its rear end portion and capable of contacting current supply means extending either from the rear or from above, and a hood pivotally mounted on a horizontal axis 65 on said iron and movable to either of two adjusted positions in one of which it protects the contact means effectively from access from the rear and in the other of which it protects the contact means effectively from access from 70 above.

5. In an arrangement of the type described, the combination of an electric iron having contact means thereon at its rear end portion and capable of contacting current supply means ex- 75

- tending either from the rear or from above, and a hood pivotally and frictionally mounted on a horizontal axis on said iron and movable to either of two adjusted positions in one of which it is held by friction substantially above said contact means and in the other of which it is held by friction substantially opposite the rear of said contact means.
6. In an arrangement of the type described, 10 the combination of an electric iron having at its heel portion two cooperating contact pins in substantially vertical position thereon and two other cooperating contact pins in substantially horizontal position thereon, and shielding means 15 movably mounted on said iron adapted in one position to prevent effective access to one set of contact pins longitudinally thereof and in another position to prevent effective access to the other set of contact pins longitudinally 20 thereof.
7. In an arrangement of the type described, the combination of an electric iron having at its rear end portion contact means thereon ac- 25 cessible either from above or from the rear, housing means on said iron shielding said contact means from the front and from both sides, and a hood movably mounted on said housing means adapted in one position to shield said contact means from the rear and adapted in an alternative position to shield said contact means from above.
8. In an arrangement of the type described, 10 the combination of an electric iron having at its rear end portion contact means thereon accessible either from above or from the rear, housing means on said iron shielding said contact means from the front and from both sides, and a hood pivotally mounted on a horizontal 15 axis on said housing means and movable to two alternative positions thereon in one of which positions the hood substantially closes said housing at the rear and in the other of which positions it substantially closes the housing at 20 the top.

RUDOLPH KOVAC.
